CLAIM

The ornamental design for a golf club headcover, as shown and described.

DESCRIPTION

FIG. 1 is a front elevation view showing a new design for a golf club headcover;

FIG. 2 is a rear elevation view thereof;

FIG. 3 is a side elevation view of thereof;

FIG. 4 is an opposing side elevation plan view thereof;

FIG. 5 is a top plan view of thereof; and,

FIG. 6 is a bottom plan view thereof.

The broken lines show portions of the golf club headcover that form no part of the claimed design.
